UNITED STATES PATENT OFFICE.

MACY A. PHELPS, OF JACKSON, MICHIGAN, ASSIGNOR TO JACKSON CUSHION SPRING COMPANY, OF JACKSON, MICHIGAN.

SPRING-CUSHION WORK.

No. 857,666.

Specification of Letters Patent.

Patented June 25, 1907.

Application filed October 6, 1906. Serial No. 337,741.

To all whom it may concern:

Be it known that I, MACY A. PHELPS, a citizen of the United States, residing at Jackson, in the county of Jackson and State of Michigan, have invented certain new and useful Improvements in Spring-Cushion Work, of which the following is a specification.

This invention relates to spring cushions. One object is to provide a spring cushion possessing rigidity of structure and resiliency in use.

Another object resides in the provision of a peculiar fastening or clip for securing the springs of the cushion to the supporting wires and frame.

With the above and other objects in view, the present invention consists in the combination and arrangement of parts hereinafter referred to, shown in the accompanying drawings, and particularly pointed out in the appended claims.

In the drawings: Figure. 1 is a top plan view of my invention; Fig. 2 is a transverse sectional view; Fig. 3 is a detail view of one of my improved fasteners prior to its connection with the work. Fig. 4 is a similar view of the fastener showing it in its applied form; Fig. 5 is a plan view of a portion of a cushion supported in a wooden frame; Fig. 6 shows a side elevation of the construction shown in Fig. 5. Figs. 7 and 8 are perspective views of clips which I employ for connecting some of the springs to the edge wires.

Referring now more particularly to Figs. 1 to 4, inclusive, I illustrate a structure particularly adapted for vehicle, furniture and analogous purposes, the reference characters 1 and 2 indicating upper and lower edge wires, forming a frame. Disposed within the edge wires are springs 3 which depend mainly for support upon the pairs of support wires 4, there being a support wire 5 near each side of the work for co-operation with the corresponding edges of the lower edge wire to firmly support the side rows of springs. These side supporting wires, if the front or rear of the cushion is rounded, curve somewhat, as shown at 6, to conform to the curvature of the border wire of the cushion; and, if desired, these side supports may terminate short of the edge wire. The springs are held firmly in proper position upon their supports by means of the fasteners 7, and each has a

pair of fingers 8 at each end with an intermediate finger 9 disposed between each pair of fingers, the intermediate fingers being the same length as the pairs of fingers or shorter, as shown. The pairs of fingers 8 are bent or otherwise turned about the lower edge wire 60 or a supporting wire and the lower convolution of the corresponding spring, while the intermediate fingers lie normally in vertical plane to have a substantial engagement with the side of the edge wire or support and 65 spring opposite to that side with which the body of the pairs of fingers contact. It will be noted that all of the fingers are directed upwardly and that the body of each of said fasteners lies beneath the plane of the lower 70 edge and support wires, whereby a bottom is produced without any rough edges to catch into the bottom covering of an upholstered article or scratch any support on which it may be resting.

Aside from the fact that I produce a double-end fastener of a single piece of metal or other suitable material, the fasteners are so arranged as to present their body centrally of the bottom of the corresponding spring to 80 support the center coils of the latter and prevent them from being forced by weight beneath the lowermost convolutions. Further, the fasteners secure the springs and wires together rigidly and permit of the removal of 85 one spring irrespective of other springs. The springs cannot separate or close together on the bottom.

Except at the front and rear of the cushion separate fasteners are not necessary, and as 90 a matter of fact, separate means are not absolutely necessary in the front and rear of the cushion. However, I do illustrate fasteners 10, which are so formed that the intermediate finger 11 may be turned into the space between the pairs of fingers 12 to provide a substantially cylindrical shape fastening, although of course, the fasteners 10 are in flat plate form prior to their cylindrical formation. I do not confine myself to any particular means for connecting the edge wires with the spring work.

Connecting the tops of adjacent rows of springs are my improved two-end fasteners, serving as means to not only aid in staying 105 the springs, but also, and principally to provide a pliable top and support upholstering material between the rows of springs. These

said top connections permit the springs to act somewhat independently and yet in connection one with another over the area affected by pressure. If desired, I may employ the stay wires 13 connecting which and the upper convolutions of the corresponding springs are my improved double-end fasteners, the stays providing a rigid top.

It is to be understood that I do not limit myself as regards the application of my improved fasteners and that I may use the same advantageously in cushion work constructed for support in a wooden frame. For instance, in Figs. 7 and 8 there is shown a series of springs mounted upon the supporting wires 14 whose ends are directed upwardly to form hooks 15 for engagement in the wooden frame 16.

One important advantage derived in the present two-end fastener resides in the fact that since it is formed of a plate or single piece of material both ends would have to become loosened or detached before the corresponding spring would become wholly loosened or detached from its fastener and support.

Obviously, the top and bottom of the cushion may be formed alike; that is to say, the top may be formed the same as the bottom of the cushion or the bottom may be formed in accordance with that form herein described as the top of the work.

What is claimed is:

1. A cushion comprising a frame, supporting wires, springs arranged upon the wires, and a fastener connecting each spring and

the corresponding supporting wires, each fastener having three fingers at each end, the outer fingers at each end being bendable about the springs and supporting wires and the intermediate finger lying throughout its length at a right angle to the body of the respective fastener and adjacent the side of the convolution of the spring and supporting wire opposite the side of the convolution of the spring and supporting wire against which the main portions of the outer fingers engage.

2. A fastener of the character described comprising a plate having three fingers at each end, one finger being disposed in a plane different than the plane of the other fingers.

3. A fastener of the character described comprising a body portion having three fingers at each end, the intermediate finger of each end lying in a plane different from the plane of the outer fingers of each end.

4. A spring cushion comprising a frame, springs within the frame, supporting wires for the support of the springs, and fasteners secured to the supporting wires and springs, each fastener having three fingers at each end for connecting them to the supporting wires and springs, one fastener lying centrally of each spring.

In testimony whereof I have signed my name to this specification in the presence of two subscribing witnesses.

MACY A. PHELPS.
